TOY SUPPORT AND OPERATING UNIT

William H. Zimbalist, Brooklyn, N. Y.

Application May 20, 1953, Serial No. 356,148

7 Claims. (Cl. 46—99)

This invention relates to toys generally referred to as stuffed toys. More particularly, the invention deals with a support and operating unit for toys of this type and kind having means for propelling the toy over a surface.

Still more particularly, the invention deals with a unit of the character described having means for operative engagement with one set of wheels of the unit for actuating a portion of the toy to impart predetermined movement thereto.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of a unit made according to my invention with part of the construction broken away, and indicating in dot and dash lines the outline of a stuffed dog supported on the unit;

Fig. 2 is a plan view of the structure as shown in Fig. 1 omitting the representation of the dog;

Fig. 3 is a partial section on the line 3—3 of Fig. 1 on an enlarged scale, with part of the construction broken away, and indicating said part in different positions in dot and dash lines; and

Fig. 4 is an enlarged sectional detailed view on the line 4—4 of Fig. 2, showing only part of the construction and omitting the background showing.

My invention deals with a support and operating unit for what is generally known as stuffed toys, and for purposes of illustration I have indicated in Fig. 1 of the drawing, in dot and dash lines, the outline of a stuffed toy dog, the unit including a mechanism extending into the tail of the dog to actuate or wag the tail in movement of the dog or the supporting unit thereof over a surface.

In practice, my improved unit comprises a frame 10 composed of two similar substantially U-shaped frame strips 11, 11', each strip having an offset end portion at 12, 12' which is welded to the opposed end 13, 13' in forming a rectangular base frame.

Opposed sides of the frame at the forward end thereof have alined apertures for receiving a front wheel shaft 14, having rubber tired wheels 15 fixed to the ends thereof outwardly of the frame. The wheels are held in spaced relation on the frame by offset members on the shaft 14, as at 16, which engage the inner surfaces of the frame sides. At the rear portion of the frame, the sides have other opposed apertures for receiving a drive wheel shaft 17 having wheels 18 similar to the wheels 15, the shaft 17 having offsets 16' similar to 16. The shaft 17 has between the side members of the frame a crank portion 19.

Pivoted to the forward end portion of the frame inwardly of the shaft 14 is a U-shaped toy supporting frame 20 pivoted to frame strips 11, 11' as seen at 21. At the rear of the frame, and rearwardly of the drive shaft 17, is a fixed U-shaped frame 22 which is fixed to the base frame as seen at 23, the frame 22 being braced to

2

maintain a rigid position by bracing strips 24. At 25 is shown the upper crosshead of the frame 22 which is considerably narrower than the base frame, as will clearly appear from Fig. 2 of the drawing, and supported on this crosshead is the operative mechanism 26 of the unit 10.

The mechanism 26 comprises an upwardly extending supporting plate 27, having an angular base flange 28 which is welded to the crosshead 25. The plate 27 has at its side edges notches 29 for receiving bent-over ears 30 of a casing 31. The casing 31 is defined by a top wall 32, side walls 33, and a bottom wall 34, the top wall terminating short of the plate 27 to form an opening 35 extending the full width of the casing.

Operating in the opening 35 and projecting from the casing is a lever 36 which may be termed a tail actuating member. The lever 36 has within the casing an offset pivot side 37 which is pivoted to an inwardly pressed bearing portion 38 on the plate 27 as seen at 39. The bearing portion 38 is provided to minimize frictional engagement of the lever in its movement on the plate 27. The other side of the lever 36 has an inwardly offset portion 40 with which a connecting rod 41 is pivoted, as seen at 42. The rod 41 has at the lower end thereof and adjacent the crank 19 reversely offset or curved portions 43 and 44. At 45 I have shown the crank coupling member comprising a plate having a curved bearing portion 46 at one end enveloping and rotatably mounted on the crank 19. The other end portion of this plate has an elongated aperture 47, through which offset 43 passes, and a metal strap or band 48 is disposed between the offset 43 and one surface of the plate 45, and has ends bent upon the opposed surface of the plate, one of which is seen at 49 in Fig. 4 of the drawing. This construction couples the connecting rod 41 with the plate and also operates to maintain alinement of the rod so as to substantially maintain its alinement with the pivot 42.

It will be noted from a consideration of Fig. 3 that the rod 41 operates in an aperture 50 in the bottom wall 34 of the casing 31.

The upper or outer end portion of the lever 36 has at one side thereof a notch 51 for receiving the coupling loop 52 of a conventional bell element 53, so that in operation of the lever 36 to the extreme positions indicated in dotted lines in Fig. 3, the bell 53 will be sounded.

It will be apparent from the foregoing description that, as the unit 10 is operated over a surface, the wheels 18 of the drive shaft 17 will operate the crank 19 to in turn actuate the lever 36 on its pivot 39 through the medium of the connecting rod 41, causing said lever to move back and forth transversely with respect to the path of travel of the unit.

For purposes of illustrating one adaptation of my invention, I have indicated in dot and dash lines in Fig. 1 of the drawing at 54 a stuffed dog, the front legs of which are indicated at 55, the rear legs at 56, and the tail at 57. It will be understood that the frame 20 is disposed within the front legs 55 with the crosshead of said frame disposed at the breast portion of the dog. By virtue of the pivotal mounting of the frame 20, this will compensate for slight variance in the dog structure, keeping in mind that the rear frame 22 is fixed and this frame must maintain a definite position within the rear legs 56. The upper crosshead 25 of the frame 22, as well as the casing 31, are disposed within the rear portion of the dog with the lever 36 extending upwardly through the tail 57. The tail 57 will be flexibly joined thereto by the oscillation of the lever.

This construction will produce a wagging of the tail, as will be apparent. The only part of the structure of the unit 10 which will be visible externally of the dog 54 will

be the connecting rod 41, the base frame, the wheels, and part of the coupling of the frames 20, 22, and the braces 24 with the frame, the front and rear legs 55 and 56 being supported directly upon the members 11, 11' of the base frame.

It will be apparent that the tail wagging will take place in movement of the toy in either direction over a surface. It will also be apparent from the foregoing that a very simple and yet sturdy unit structure is provided, and one in which a simple direct mechanical motion is provided which is not likely to get out of order or need repair.

Having fully described my invention, what I claim as new and desire to secure by Letters Patent is:

1. A stuffed animal supporting and operating unit, said unit comprising a base frame, a stuffed animal mounted upon the frame, two wheeled shafts rotatably mounted in opposed end portions of the frame, one shaft having a crank portion, a pair of U-shaped supporting frames extending upwardly from the base frame and arranged in said animal, one of said supporting frames being arranged adjacent the crank shaft and having an upper end extending to the upper rear portion of the stuffed animal, said last named frame having an actuating mechanism supported on the upper end thereof, said mechanism comprising a casing, a lever pivoted to said casing, means comprising a connecting rod for operatively coupling said lever with the crank of said crank shaft, said lever having a projecting part forming an actuated member, the animal including a part enveloping said member and actuated by the operation of said mechanism, and means for bracing the first named supporting frame to maintain predetermined position with respect to said base frame.

2. A stuffed animal supporting and operating unit, said unit comprising a base frame, a stuffed animal mounted upon the frame, two wheeled shafts rotatably mounted in opposed end portions of the frame, one shaft having a crank portion, a pair of U-shaped supporting frames extending upwardly from the base frame and arranged in said animal, one of said supporting frames being arranged adjacent the crank shaft and having an upper end extending to the upper rear portion of the stuffed animal, said last named frame having an actuating mechanism supported on the upper end thereof, said mechanism comprising a casing, a lever pivoted to said casing, means comprising a connecting rod for operatively coupling said lever with the crank of said crank shaft, said lever having a projecting part forming an actuated member, the animal including a part enveloping said member and actuated by the operation of said mechanism, means for bracing the first named supporting frame to maintain predetermined position with respect to said base frame, the coupling of said connecting rod with the crank comprising a plate having a curved bearing portion enveloping the crank, an apertured portion in which the connecting rod is mounted, and means securing the connecting rod to said plate.

3. The combination with a stuffed animal, having a body, front and rear leg members and a tail, of a supporting and operating unit comprising a wheeled base frame extending longitudinally of the animal, two U-shaped supporting frames extending upwardly from the base frame, one supporting frame being pivotally mounted on the base frame and being disposed within the front legs and part of the body of the animal, the other supporting frame being fixedly secured to the base frame and disposed within the rear legs and having a crosshead disposed within the upper, rear portion of the body adjacent the tail, a wheel operated crank shaft in the base frame adjacent said last named supporting frame, means coupled with the crosshead of the last named frame for pivotally mounting a lever in connection therewith on an axis to swing transversely of the body, said lever including a part extending into the tail,

5 a connecting rod pivotally coupled with one end of said lever, and means rotatably coupling the other end of said connecting rod with the crank of said crank shaft, whereby, in the operation of the wheels of the crank shaft, said rod will actuate said lever and transmit transverse reciprocating movement to the tail of said animal mounted on said lever.

4. The combination with a stuffed animal, having a body, front and rear leg members and a tail, of a supporting and operating unit comprising a wheeled base frame extending longitudinally of the animal, two U-shaped supporting frames extending upwardly from the base frame, one supporting frame being pivotally mounted on the base frame and being disposed within the front legs and part of the body of the animal, the other supporting frame being fixedly secured to the base frame and disposed within the rear legs and having a crosshead disposed within the upper, rear portion of the body adjacent the tail, a wheel operated crank shaft in the base frame adjacent said last named supporting frame, means coupled with the crosshead of the last named frame for pivotally mounting a lever in connection therewith on an axis to swing transversely of the body, said lever including a part extending into the tail, a connecting rod pivotally coupled with one end of said lever, means rotatably coupling the other end of said connecting rod with the crank of said crank shaft, whereby, in the operation of the wheels of the crank shaft, said rod will actuate said lever and transmit transverse reciprocating movement to the tail of said animal mounted on said lever, and the means pivotally mounting the lever on said crosshead comprising a plate having an offset bearing portion, where the lever is pivoted to said plate.

5. The combination with a stuffed animal, having a body, front and rear leg members and a tail, of a supporting and operating unit comprising a wheeled base frame extending longitudinally of the animal, two U-shaped supporting frames extending upwardly from the base frame, one supporting frame being pivotally mounted on the base frame and being disposed within the front legs and part of the body of the animal, the other supporting frame being fixedly secured to the base frame and disposed within the rear legs and having a crosshead disposed within the upper, rear portion of the body adjacent the tail, a wheel operated crank shaft in the base frame adjacent said last named supporting frame, means coupled with the crosshead of the last named frame for pivotally mounting a lever in connection therewith on an axis to swing transversely of the body, said lever including a part extending into the tail, a connecting rod pivotally coupled with one end of said lever, means rotatably coupling the other end of said connecting rod with the crank of said crank shaft, whereby, in the operation of the wheels of the crank shaft, said rod will actuate said lever and transmit transverse reciprocating movement to the tail of said animal mounted on said lever, the means pivotally mounting the lever on said crosshead comprising a plate having an offset bearing portion, where the lever is pivoted to said plate, and the free end of said part of said lever including a sound producing element.

6. A stuffed dog support and operating unit of the class described, comprising a wheeled base frame, a stuffed dog mounted upon said frame, two upwardly extending U-shaped supporting frame members on the base frame, said dog comprising a body, front and rear legs and a tail, one supporting frame being pivotally mounted on the base frame and arranged in the front legs and body, the other supporting frame being fixedly secured to the base frame and arranged in the rear legs and body, said fixed frame supporting, at its upper end, a mechanism including a movable member extending into said tail, the wheeled base frame including a rotatable crank shaft, said mechanism including a pivoted lever, of which said member constitutes a part, and means com-

prising a connecting rod coupled with the crank of said crank shaft and pivoted to said lever for actuating said tail in movement of the unit over a surface.

7. A stuffed dog support and operating unit of the class described, comprising a wheeled base frame, a stuffed dog mounted upon said frame, two upwardly extending U-shaped supporting frame members on the base frame, said dog comprising a body, front and rear legs and a tail, one supporting frame being pivotally mounted on the base frame and arranged in the front legs and body, the other supporting frame being fixedly secured to the base frame and arranged in the rear legs and body, said fixed frame supporting, at its upper end, a mechanism including a movable member extending into said tail, the wheeled base frame including a rotatable crank shaft, 15 said mechanism including a pivoted lever, of which said member constitutes a part, means comprising a connecting rod coupled with the crank of said crank shaft and pivoted to said lever for actuating said tail in movement

of the unit over a surface, and said member including a sound producing element disposed within the tail.
